UNITED STATES PATENT OFFICE

125,313

DESIGN FOR A BOX OR SIMILAR COSMETIC CONTAINER

Tommi Parzinger, New York, N. Y., assignor to Harriet Hubbard Ayer, Inc., New York, N. Y., a corporation of New York

Application March 14, 1940, Serial No. 90,913

Term of patent 3½ years

To all whom it may concern:

Be it known that I, Tommi Parzinger, a citizen of Germany, residing in the city, county, and State of New York, have invented a new, original, and ornamental Design for a Box or Similar Cosmetic Container, of which the following is a specification, reference being had to the accompanying drawing, forming a part thereof, in which:

The figure is a perspective view of a box or similar cosmetic container showing my new design.

I claim:

The ornamental design for a box or similar cosmetic container, as shown.

TOMMI PARZINGER.
